UMBRELLA

Charles A. Suel, New York, and Victor Axelrad,
Forest Hills, N. Y.

Application September 8, 1947, Serial No. 772,840

1 Claim. (Cl. 135—30)

1

This invention relates to umbrellas, and in particular is directed to improvements in the construction of the notch and runner of an umbrella frame including the pivoted ends of the extensible members (ribs and stretchers) secured therein.

Accordingly, it is one of the objects of this invention to provide an umbrella frame of such construction that the notches and runners present a sturdy arrangement of bearing members to receive the associated members of the ribs and stretchers.

Another object of this invention is to provide an umbrella frame of markedly increased sturdiness of construction, with consequent enhancement in the protection of the fabric against destruction or spoiling.

A further object of this invention is to provide an umbrella frame of markedly enhanced sturdiness by using notches and runners and associated elements that are readily assembled and which may be readily disassembled for repair.

The foregoing and other objects of the invention are achieved by a structure embodying our concepts as shown in the forms thereof illustrated in the accompanying drawings wherein:

Fig. 1 is a diagrammatic representation, in sectional view and partially broken, showing an umbrella frame in erected position.

Fig. 2 is an enlarged view, in vertical section, of the form of notch illustrated in Fig. 1, showing fragmentary portions of the ribs adjacent the notch, in collapsed position.

Fig. 3 is a plan view of the embodiment illustrated in Fig. 2.

Fig. 4 is an enlarged view, in vertical position, of the form of runner illustrated in Fig. 1, and fragmentary portions of the stretchers adjacent the runner, in collapsed position.

Fig. 5 is a plan view of the runner illustrated in Fig. 4.

Fig. 6 is a plan view of a modified form of notch or runner in which the ribs or stretchers, shown in fragmentary portions adjacent thereto, are secured by means of roller bearings set within the notch or runner.

Fig. 7 is a view taken on the line 7—7 of Fig. 6.

Fig. 8 is a perspective view of a roller forming the bearing used in the embodiment illustrated in Figs. 6 and 7.

Fig. 9 is a perspective view of a fragmentary portion of a rib or stretcher showing the manner of mounting the same on the roller illustrated in Fig. 8.

Fig. 10 is a vertical cross-sectional view of another modified form of a notch or runner em-

2

bodying the concepts of this invention in the form of cusps.

Fig. 11 is a perspective view of a spherical member provided with a stem forming the means for securing a rib or stretcher thereto for mounting within the notch illustrated in Fig. 2 or 3, or the runner illustrated in Fig. 4 or 5.

Fig. 12 is a perspective view showing the assemblage of the spherical member illustrated in Fig. 11 with a rib or stretcher.

Fig. 13 is a vertical cross-sectional view of a notch embodying the concept of this invention as adapted for the construction of a folding umbrella.

Fig. 14 is a vertical cross-sectional view of a further modified form of a notch or runner in which the annular members have an annular semi-circular groove.

Referring now in greater detail to the drawings, the numeral 20 indicates the rod or stick of an umbrella frame represented in this instance by a tubular member of conventional construction. The notch is indicated by the numeral 22 and the runner or sleeve by the numeral 24. The ribs 26 and the struts or stretchers 28 are connected to each other as at 30 in conventional fashion.

Referring now to Figs. 2 and 3, the notch 22 comprises a pair of symmetrically disposed annular members 32 having an inner flange 34, a flat mid-section 36, and an outer concave or semi-circular section 38. The flange 34 sheathes the rod 20. The concave section 38 is provided with a plurality of radially disposed slots 40.

These two annular members form the two halves of the notch and they are held in cooperating position by an upper retaining member 42 and a lower retaining member 44. The retaining members comprise a tubular section 46 which sheathes the rod 20 and a flange 48. The flange 48 is shouldered as at 50, this shoulder being adapted to receive the flange 34, while the flange 48 bears against the flat mid-section 36 of the annular members. The tubular section 46 of members 42 and 44 are securely connected to the rod 20 by means of the cross pins 52. The rigidity of the assemblage is further insured by means of the vertical pin 54 which passes through the flanges

48 of the retaining members and the mid-sections 36 of the two halves of the notch. The rib 26 is provided at its lower extremity with a ball or spherical member 60 which is pivotally positioned within a radial slot and seated securely within

55 the symmetrically disposed and locked semi-

circular sections 38 of the two annular members forming the notch.

In the form of sleeve or runner illustrated in Figs. 4 and 5, there is shown, mounted on the rod 20, a slideable sleeve 70 flanged as at 72. A pair of symmetrically disposed annular members 74 are secured to the sleeve. The annular members comprise an inner flange 76, a relatively flat mid-section 78, and an outer concave or semi-circular section 80. The concave sections are provided with a plurality of radially disposed slots 82 similar to those of the notch illustrated in Figs. 2 and 3. The upper annular member 74 is seated against the lower face 84 of the flange 72 which is appropriately shaped to accomplish that purpose. The lower annular member 74 is secured in cooperating position with the upper annular member by means of the nut 86 mounted on the threaded portion 88 of the sleeve 70. The rigidity of the assemblage is further insured by means of a vertical pin 87 which passes through the flange 72 of the sleeve 70 and the members 74 and also through the nut 86. The nut 86 is flattened as at 89 so that it may be gripped by a wrench or other appropriate tool. Seated within the radial slots 82 are the lower ends of the stretchers 28, these ends being provided with a ball member 60. The stretchers are mounted pivotally and securely within the cooperating halves of the annular members, and their functioning is similar to that of the ribs described with respect to the notch illustrated in Figs. 2 and 3. It will be apparent that in these forms of notches and runners the ribs and stretchers are securely retained and their mechanical operation or function is fundamentally that of a ball bearing mounting.

Referring now to the forms illustrated in Figs. 6 and 7, there is shown a structure comprising a pair of annular members adapted for operation either as a notch or a runner, in which is embodied the roller bearing principle. The symmetrically disposed annular members 90 are similar to those illustrated in Figs. 4 and 5. These members have inner flanges 92, mid-sections 94 and outer concave or semi-circular sections 96. When used as a notch they are secured to the rod 20 and held in locked cooperating position by means of upper and lower retaining members of appropriate size and conformation, the retaining members being securely fastened to the rod. When used as part of the runner, the pair of cooperating annular members 90 may be assembled on a slideable collar or sleeve in the manner illustrated in Figs. 4 and 5. The semi-circular sections 96 are provided with a plurality of radially disposed slots 98. Positioned within the slotted portions are the extremities of the ribs or stretchers, as the case may be, which are secured to the rollers 100. As shown in Figs. 8 and 9, the rollers 100 are flanged as at 102. The lower flat end of the rib or stretcher, as the case may be, is wrapped around the stem 104 of the roller 100 and securely held in position against lateral movement by the flanges 102. It will be apparent that the rib or stretcher is securely held in position in this embodiment and that the pivotal motion of the rib or stretcher is that of a roller bearing.

In Fig. 10 there is shown another modification of a pair of symmetrically disposed members which form the rib or stretcher holding elements of a notch or runner. These annular members 110 are provided with a plurality of hemispherical cups or cusps 114 which in turn are partially

cut away to form a plurality of radially disposed slots 116. The members 110 may be securely connected together and used either in the assemblage of a notch or in the assemblage of a runner by appropriate means. When used as a notch they are secured to the rod of an umbrella by retaining members of appropriate size and conformation as hereinabove described. When used in the assemblage of a runner they are mounted on a sleeve or collar of appropriate size and conformation and securely fastened thereto. The ribs or stretchers, as the case may be, are positioned within a pair of symmetrically disposed cusps by providing the ribs or stretchers with a ball or spherical extremity such as, for example, that illustrated in Figs. 11 and 12. The operation of the assemblage is similar to that of the embodiments illustrated in Figs. 2 and 3 or Figs. 4 and 5.

In Fig. 14 there is shown a modified form of the structure illustrated in Fig. 10. In this instance the annular member 111 is provided with an annular semi-circular or concave groove or channel 113 and a plurality of radial slots 115. The members 111 may be positioned and locked, either for use in a notch or runner assemblage, in the same manner as the members shown in Fig. 10. The ends of the extensible members, i. e., the ribs or stretchers, are positioned within the slots and held therein either by means of spherical elements as shown in Figs. 2, 3, 4 and 5 or roller members as shown in Figs. 6 and 7.

The embodiment illustrated in Fig. 13 shows a form adapted for use as a component member of a folding umbrella. The numeral 120 indicates a tubular member forming part of the rod of an umbrella. Set within the tubular member 120 is a stud 122 provided with a flange 124 and an axially disposed threaded bolt 126. The flange 124 forms the seat against which is positioned the upper of a pair of symmetrically disposed annular members 128 similar to the annular members 32. The lower annular member 128 is held in locked engagement with the upper annular member by means of retaining member 130 which is similar to the retaining members 42 and 44 illustrated in Fig. 3, the same being secured to the rod 120 by means of the cross pin 132. To achieve additional rigidity of the notch the same may be provided with a pin 134 which passes through the flange 136 of the retaining member and the flat mid-sections 138 of the annular members 128. The concave or semi-circular sections 140 of the annular members 128 are provided with a plurality of radially disposed slots 142. The ribs, provided at their ends with appropriate spherical or roller members, are positioned within the slots in the manner similar to that illustrated in Figs. 2 and 3, or 6 and 7.

In Figs. 11 and 12 there are shown means for the assemblage of a rib or stretcher provided with a spherical extremity. The assemblage comprises a ball 60 having a short stem 150. The stem 150 may be set within the lower end of a rib or stretcher of conventional channel-like formation. The end may then be crimped over the stem so as securely to fasten these two elements together.

It will be understood that the embodiments shown in the accompanying drawings are illustrative of the means for accomplishing the concept of our invention and, therefore, that it is possible to provide various modifications of the invention without departing from the spirit and scope thereof. Accordingly, the appended claim

is to be understood as defining our invention within its full meaning and scope.

We claim:

A structure for pivotally positioning an extensible member of an umbrella frame within the notches and runners thereof which comprises: a roller having end flanges intermediate which flanges there is securely wrapped around the roller a flattened portion at the extremity of an extensible member.
